[57] **CLAIM**

The ornamental design for monitor buttons, as shown and described.

DESCRIPTION

FIG. 1 is a front view of a first embodiment of monitor buttons showing my new design;

FIG. 2 is a right side view thereof;

FIG. 3 is a left side view thereof;

FIG. 4 is a perspective view thereof;

FIG. 5 is a front view of a second embodiment of monitor buttons showing my new design;

FIG. 6 is a right side view thereof;

FIG. 7 is a left side view thereof; and,

FIG. 8 is a perspective view thereof.

The monitor is shown in broken lines in the views for illustrative purposes only and form no part of the claimed design.
